UNITED STATES PATENT OFFICE.

HARRY DEL MAR, OF NEW YORK, N. Y., ASSIGNOR TO BOILERS AND ENGINEERING COMPANY, OF JERSEY CITY, NEW JERSEY, A CORPORATION OF NEW JERSEY.

STEAM-GENERATOR.

No. 878,942.

Specification of Letters Patent.

Patented Feb. 11, 1908.

Application filed March 14, 1907. Serial No. 362,306.

To all whom it may concern:

Be it known that I, HARRY DEL MAR, of the city, county, and State of New York, have invented a new and useful Improvement 5 in Steam-Generators, of which the following is a full, clear, and exact description.

My invention relates to improvements in steam generators, and the object of my invention is to produce a steam generator 10 which combines the elements of a fire tube and water tube boiler, and which utilizes the products of combustion so that the heat does not have a direct passage through the fire tube series, but is deflected and given such a 15 course that the heat is practically all absorbed by the water in the boiler and tubes before the smoke enters the stack.

Another object of my invention is to produce a sectional boiler of the kind described, 20 with the sections arranged so that large power can be taken into a fire room in small sections, and assembled by connecting the several elements or drums by means of water tubes or water legs, and the whole set in position 25 in suitable frames, each element having a frame of its own, and the several frames can be joined together to form the side walls of the boiler, thus having a boiler with a setting which will stand the effects of expansion 30 and contraction without displacing the setting, and giving longer life to the boiler.

In carrying out this idea, I can make the boiler of either horizontal or vertical type, and the essential thing is to have the several 35 elements or drums through which the fire tubes pass, connected by other elements or drums through which water tubes pass, the fire tubes of the first elements entering the drums of the second elements, and the water 40 legs or tubes connecting the first mentioned drums. All this to the end that I can get a compact, relatively cheap, and economical steam generator, which will occupy relatively small space.

With these ends in view, my invention 45 consists of certain features of construction and combinations of parts which will be hereinafter described and claimed.

Reference as to be had to the accompanying drawings forming part of this specifica-

tion, in which similar figures and letters of reference indicate corresponding parts in all the views.

Figure 1 is a longitudinal section of the horizontal boiler showing my improvements. 55 Fig. 2 is a cross section on the line 2.2 of Fig. 1. Fig. 3 is a cross section on the line 3.3 of Fig. 1. Fig. 4 is a cross section on the line 4.4 of Fig. 1, Fig. 5 is a cross section on the line 5.5 of Fig. 1, Fig. 6 is a vertical section of the boiler, Fig. 7 is a cross section on the line 7.7 of Fig. 6, and Fig. 8 is a detail elevation showing a modified form of connection between a pair of drums.

Referring to Figs. 1 to 5, it will be seen 65 that the boiler is made up of a series of drums 10, 10^a and 10^b, which are spaced apart, and the several elements or drums connected by intermediate drums, 11 and 11^a. Obviously this arrangement can be carried out indefinitely, that is, any desired number of drums within reasonable limits, can be used, and I prefer to arrange them as shown, with the successive drums lower than the preceding ones, so that the sediment will settle in the 75 lower drum, as for instance in the drum 10^b, from which it can be blown off through ordinary blow-off cocks. The boiler can have any usual setting, and I have shown it arranged over a grate 12, which can be of any 80 preferred kind, and which is shown arranged in front of the ordinary bridge wall 13. The course of the products of combustion is therefore back over the bridge wall 13, thence up behind the boiler and forward through the 85 fire tubes 14, which extend through the drum 10^b. Here the products of combustion enter the drum 11^a, and are deflected, and the heat is absorbed to a further extent by the water which passes through the water 90 tubes 15, which connect the parts 10^a and 10^b. From the drum 11^a the products of combustion pass forward through the fire tubes 16 in the drum 10^a, and enter the drum 11, where they are deflected, the heat is ab- 95 sorbed by the water in the second series of water tubes 15, and the gases then pass forward through the fire tubes 17 in the drum 10, to the chamber 18, and the smoke then passes out through the smoke stack 19. It 100

will be seen that by this time the water in the boiler has pretty thoroughly absorbed the heat from the products of combustion.

Arranged above the boiler proper is a steam drum 20, which also serves as an equalizer, and I prefer to use at least two of these drums, so that the boiler can be set up in sections to better advantage, and the two sections connect by the coupling 21. The sections 20 of the steam drum also connect with the parts 10, 10^a and 10^b, by water legs 22, and in order that the water may thoroughly absorb the heat from the gases, I prefer to have the water line in the lower part of the steam drum sections, as indicated by broken lines in Fig. 1.

In making up the drums 11 and 11^a, the top part of the drum can be made of iron, as shown best in Fig. 3, and this covered with fire brick 23, and this top part of the drum can conveniently have flanges 25, which rest on the brick supports 24. The lower part of the drum can be conveniently made of fire-brick 26, but I do not claim the drum structure in detail, and on the other hand do not limit my invention to any particular form of drum.

It will be readily seen that the drums 10, 10^a and 10^b, or 11 and 11^a, can be made up in any convenient way, but it is essential that the several drums be separable so that the boiler can be taken into the fire room in sections, and built up as shown. The several drums should be provided with suitable manholes, so that they can be entered, and it is better to make the drum 10^a a little longer than the parts 11 or 11^a, so that one can enter the latter, cut out the tubes if necessary, and remove the tubes 16 through the drum 11 or 11^a.

By reference to the drawing it will be seen that I arrange the water tubes 15 near the periphery of the drums, but the arrangement of the several tubes is not material, and I do not limit myself to the use of these water tubes, as the connection between the parts 10, 10^a and 10^b can be any suitable water connection. This is shown clearly in Fig. 8 and will be referred to hereinafter.

In Figs. 6 to 8 it will be observed that I can produce a vertical boiler of the same type with practically no change, and it amounts in fact to setting the boiler shown in Fig. 1, on end. Some slight modifications are, however, necessary. For instance, in this case the boiler is inclosed by a suitable shell 27, and the several drums 10, 10^a and 10^b are connected by an equalizer 28, which connects directly with the drums by suitable pipes 29. Several of the drums can be supported on suitable brackets 30 attached to the boiler casing, or they can be supported in any other convenient way. The casing merges in the

stack 31, in which I have shown a suitable damper 32, and in the vertical type of boiler of course the steam drum 20 is dispensed with, but the steam can be taken off through the pipe 10^c connecting with the top of the section 10^b. In this vertical boiler the drum 10 is relatively short, and the gases pass upward through flues or tubes 34 in the drum, and the drum is provided with a blow-off pipe 33. The drum 11 has vertical water tubes 35 connecting the parts 10 and 10^a, while fire tubes 36 extend through the drum 10^a and into the drum 11^a, and this has water tubes 37 connecting the drum 10^a with the drum 10^b, while fire tubes 38 extend through the latter. In this case, as in the structure shown in Fig. 1, it will be seen that the fire tubes and water tubes or connections, alternate, and so the water in the drum first absorbs the heat from the fire tubes, while the water in the water tubes next absorbs the heat from the drums, through which they pass, and in this way the heat is fully utilized.

To illustrate the fact that other connections can be used instead of water tubes 35 and 15, I show in Fig. 8 the drums 10 and 10^a connecting with couplings 39, which deliver into saddles 40, which connect by the water legs 41.

The foregoing description has made it clear that I make a compact economical boiler, which will have good steam qualities, and that the boiler can be very conveniently set up in a relatively small space.

Having thus fully described my invention, I claim as new and desire to secure by Letters Patent:

1. A boiler of the kind described, comprising a series of water containing shells connected by water tubes and separated by combustion chambers, and fire flues extending through the several water containing shells, the said fire flues in each section being out of alinement with the fire flues of the next section.

2. A boiler of the kind described having a plurality of water containing shells with fire flues therethrough, with the fire flues of adjacent shells out of alinement each shell being on a different plane from the one next to it, and with the rear shell the lowest, to provide for settling at this point, and water tubes connecting the several shells.

3. A boiler of the kind described, having a plurality of shells, with the fire box and combustion chamber under the shell series, each shell having a series of fire flues approximately filling one-half the shell, with the tube series arranged alternately so as to direct the gases of combustion in an indirect course through the different tube series.

4. A boiler of the kind described, having a plurality of shells with a fire box and com-

bustion chamber under the shell series, each shell having a series of fire flues approximately filling one-half the shell, with the tube series arranged alternately so as to direct the gases of combustion in an indirect course through the different tube series, combustion chambers separating the several shells, and water tubes connecting the shells and leading through the combustion chambers.

10 5. A steam generator comprising a series of water containing shells, each shell having

a series of fire flues approximately filling one-half the shell, with the tube series arranged alternately so as to direct the gases of combustion in an indirect course through the several tube series, and water tubes connecting the several shells. 15
